INVENTOR.

Walter Webb

BY *George J. Webster*
ATTORNEY

UNITED STATES PATENT OFFICE.

WALTER WEBB, OF STOCKTON, CALIFORNIA.

SAFETY AUTO SIGNAL.

Application filed November 16, 1923. Serial No. 675,147.

To all whom it may concern:

Be it known that I, WALTER WEBB, a citizen of the United States, residing at Stockton, county of San Joaquin, State of California, have invented certain new and useful Improvements in Safety Auto Signals; and I do declare the following to be a full, clear, and exact description of the same, reference being had to the accompanying drawings, and to the characters of reference marked thereon, which form a part of this application.

This invention relates to improvements in mechanical signal devices for motor vehicles of all kinds; my principal object being to provide a signal of this general character having an arm adapted to be raised to any of the legally and arbitrarily designated positions at the will of the driver to denote his intent to turn his vehicle to the right or the left, or to stop, the signal being arranged to be mounted on a rear fender of the vehicle or similar location so as to be readily visible to any driver behind or in front of the vehicle on which the signal is mounted.

Another object is to provide a simple means for enabling the outline of the signal arm, and its relative setting when extended, being readily seen in the dark, so that my signal is as effective at night as in the day time.

The use of my signal will of course obviate the necessity of extending the hand to give signals as is at present commonly done, and which at best is a crude and very often inefficient means of giving signals.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views:

Fig. 1 is a perspective outline of an automobile, showing my improved signal installed thereon.

Fig. 2 is a vertical section of the signal detached.

Fig. 3 is a cross section of the same, the signal arm being in its closed position.

Referring now more particularly to the characters of reference on the drawings, the

numeral 1 denotes in general an automobile, having rear wheel-fenders 2, on one of which, preferably the left hand one, my improved signal device is mounted.

This comprises a vertical casing 3, preferably made in two vertical and symmetrical sections suitably connected together, and provided with horizontal brackets 4 at its base whereby to attach the same to the fender.

Pivoted in the casing adjacent the upper end and outer edge thereof on a horizontal pin 5 extending in a plane longitudinally of the vehicle is a signal arm 6, adapted to be normally concealed within the casing, the latter having a vertical slot 7 in its outer edge to enable the arm to pass into the casing.

The arm is raised from its downwardly projecting and concealed position by means of a flexible cable or wire 8 suitably attached at one end to a lug 9 projecting radially from the hub 10 of the arm, said wire leaving the bottom and rear edge of the casing through a protective tube 11 and being run thence to a point where it may be suitably manipulated by the driver. On pulling this cable different distances, the arm is raised to the various signal-giving positions, as indicated in Fig. 2.

The arm is automatically returned from any extended position to which it may have been moved, to its concealed position in the casing when the pull on the cable is released by means of a spring 12 of suitable nature, attached at one end to the hub 10 and to the casing at the other end.

A resilient bumper block 13 is mounted in the bottom of the casing inwardly of the arm, to form a stop for the arm when the latter is returned to the casing by the spring.

Mounted in the casing inwardly of the space occupied by the arm is an electric light bulb 14 backed by a reflector 15, the light being connected in a circuit in any suitable manner.

The reflector is shaped and disposed to throw the rays of light from the bulb lengthwise onto the arm when the latter is projected from the casing, the actual source of light being invisible. To cause the light to throw onto the sides of the arm and to bring the same sharply into relief without any shadow along the edge farthest from the light, the arm is made wedge-shaped in

cross section, with the thin edge facing downwardly or toward the light, as clearly shown.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A signal device for motor vehicles slotted to receive the arm and the latter being immovably mounted on a vehicle, and an arm pivoted in the casing and normally concealed therein, one edge of the casing being slotted to receive the arm and the latter being adapted to be rotated about its pivot so as to project from the casing, and a source of light immovably mounted and concealed in the casing independent of the arm, and arranged so that the rays of light will be projected from the slot and onto the arm.

2. A signal device, for motor vehicles comprising a vertical casing arranged to be immovably mounted on a vehicle, and an arm pivoted in the casing and normally concealed therein, but arranged to be swung out of the same at will, and a source of light immovably mounted and concealed in the casing and arranged so that the rays of light will be projected from the slot and onto the arm, the latter being wedge-shaped in cross section with its thinnest edge facing the light, whereby to cause some of the light rays to be thrown against the arm to bring the latter into sharp relief.

3. A signal device for motor vehicles comprising a vertical casing slotted up one edge, an immovable source of light fixed in the casing and facing the slot, and an arm pivoted in the casing and facing the slot, and arranged to be swung into and out of the slot, the arm being symmetrically wedge-shaped with its thinnest edge facing the light, whereby certain of the light rays will be thrown against both sides of the arm to cause the same to be sharply outlined both from ahead and behind the signal.

In testimony whereof I affix my signature.

WALTER WEBB.
